UNITED STATES PATENT OFFICE.

EDWARD PRENDERGAST, OF ST. LOUIS, MISSOURI.

GRADING-MACHINE

1,278,382.

Specification of Letters Patent. Patented Sept. 10, 1918.

Application filed November 30, 1917. Serial No. 204,749.

To all whom it may concern:

Be it known that I, EDWARD PRENDERGAST, a citizen of the United States, and resident of St. Louis and State of Missouri, have invented certain new and useful Improvements in Grading-Machines, of which the following is a specification containing a full, clear, and exact description, reference being had to the accompanying drawings, forming a part thereof.

My invention relates to certain new and useful improvements in "grading machines" and has for its special object the construction of a machine which by one operation or once passing over the surface of the highway, it grades the surface and at the same time rolls it and makes it ready for the application of material out of which the highway is to be made.

In the drawings:

Figure 1 is a top plan view of my invention.

Fig. 2 is an enlarged plan view of the forward portion of my invention, illustrating the manner of connecting the grading members together.

Fig. 3 is an enlarged fragmental section taken on a line 3—3 of Fig. 1.

Fig. 4 is an enlarged fragmental section taken on a line 4—4 of Fig. 1.

Fig. 5 is a view of a king bolt for connecting the forward end of the grading members together.

Fig. 6 is a side elevation of my invention.

Fig. 7 is an enlarged top plan view of the bearings for the swivel roller shaft.

Fig. 8 is an enlarged top plan view of the channel that supports the swivel bearings with bearing removed.

Fig. 9 is an enlarged side view of a portion of the frame work illustrating the swivel bearings for the shaft of the forward rollers.

Fig. 10 is a sectional view taken on a line 10—10 of Fig. 7, of a portion of one of the swivel bearings.

Fig. 11 is a side view of a pivoted arm to which the motive power is attached to operate or pull the machine.

Fig. 12 is a top plan view of the same.

Fig. 13 is a fragmentary view of the grading members, showing the means of connecting the same together.

Fig. 14 is a section on a line 14—14 of Fig. 13.

Fig. 15 is an enlarged top plan view of the frame work with parts broken away, in which the rear rollers are mounted.

Fig. 16 is an enlarged top plan view of one corner of the rear roller frame work illustrating the connection between said frame work and one of the side channel beams, and also a top plan view of a drag or leveler secured to one corner of the machine.

Fig. 17 is a fragmentary side elevation of one of the channel beams taken on a line 17—17 of Fig. 16.

Fig. 18 is an enlarged fragmental elevation taken on a line 18—18 of Fig. 16 looking in the direction of the arrows, with channel beams 21 removed.

Fig. 19 is a plan view of one of the stay or T-bars with parts broken away, and

Fig. 20 is a plan view of one of the I-beams, these beams being employed for the adjustment of the machine.

Referring to the drawings, 21 indicates channels which form the forward frame work of the machine and to which are secured the adjustable cutter blades 22. The forward ends of the channels 21 are pivotally connected together by means of hinged members 23 and 24 and the king pin 25. Secured to the channels 21 are T-bars 26 and 27, the ends of these T-bars are connected to the channels 21 as illustrated in Figs. 13 and 14, wherein the angles 28 are employed for such purpose.

In the illustrations, Fig. 1, the machine is shown at its maximum adjustment and if it is desired to adjust the machine or make it narrower in width, so as to not grade and finish as wide a surface, the machine may be adjusted as shown in dotted lines, in which event I use T-bars 29 for such purpose, said T-bars 29 being the same as 26 and 27, only of different lengths.

Secured to the channels 21 are pivoted pulling arms 30 to which the motive power is attached to operate the machine. Mounted on the channels 21 between the T-bars 26 and 27 are swivel bearings 31 in which is mounted a roller shaft 32, and mounted on the roller shaft 32 are a series of rollers 33 which are keyed thereto in any suitable

mechanical manner. The rollers 33 form the first unit of rollers and are positioned in the forward portion of the machine.

Secured to the rear ends of the channels 5 21 is a rectangular frame, formed of longitudinal I-beams 34 and transverse or end channel beams 35. The longitudinal I-beams 34 and the end channels 35 being connected together as illustrated in Figs. 15 and 16 by 10 means of angles 36 and bolts 37.

Intermediate of the channel beams 35 are I-beams 38 and 39. Mounted on one of the end channels 35 and on the I-beam 39 are shaft bearings 40 in which is mounted a roller 15 shaft 41, and mounted on the other end on channel 35 and I-beam 38 are shaft bearings 42 and 43, in which is mounted a roller shaft 44.

Mounted on the shaft 44 are a series of 20 rollers 45, and mounted on the shaft 41 are a series of rollers 46. These rollers are mounted on their respective shafts and held in the desired position thereon by means of set screws, collars or in any suitable mechanical 25 manner.

It will be observed in this connection that the forward set or unit of rollers and the rear set may be varied and are so arranged that the rear set over-laps the forward set.

30 The rollers answer as wheels for the machine and if desired only one roller may be used in front which will answer as a front wheel, and two rollers used in the rear which will answer as the two rear wheels.

35 If it is desired to shorten the width of the rectangular frame in which the series of rear rollers are mounted, I employ shorter I-beams 47.

By having the machine equipped with 40 different length T-bars such as 26 and 27 and 29 and different length I-beams such as 34 and 47, the width of the machine may be varied as desired.

The I-beams 21 and the rear rectangular 45 frame work in which the rear rollers are mounted constitute the frame work of the machine, and this frame work may be bodily adjusted by using different thickness filler plates 48 under the shaft bearings for the 50 rear rollers, and different thickness plates 49 under the swivel bearings for the front rollers.

In place of bodily adjusting the frame work of the machine, the cutter plates or 55 bars 22 may be adjusted on the angle bars 21. This is accomplished by providing the cutter bars or plates 22 with vertical elongated slots 50 in which is located a bolt 51 screw seated in the angle bars.

60 Any number of cutter plates or cutter bars 22 may be employed on each angle beam, and they may be independently adjusted. In the rear of the cutter plates on each side of the machine are pivoted drags 52. These drags 65 may be made of any form and are bodily ad-

justable on the shafts 53 or the drags may be inclined on the bearing 54. The forward end of the drags are connected to the angles by means of a connecting rod 55, which is adjustable by means of a turn buckle 56.

70 The rod 55 is pivotally connected at both ends so as to permit the same to assume different positions corresponding to the adjustment of the drags.

In the operation of the machine, the loose dirt planed off by the machine will accumulate in ridges along the sides of the machine adjacent to the rear end of the cutter bars or plates on each side of the machine, and by the movement of these drags 52 the loose 80 dirt or material may be distributed as desired, depending upon the adjustment of the drags.

By above adjustment of the drags the loose earth piled up by the machine may be distributed in a thin horizontal layer of any thickness, or an inclined layer, or the entire body of loose earth may be distributed away from the path of travel of the cutter plates.

85 As illustrated the drags 52 are made out 90 of channels to which the cutter plates are adjustably secured.

Having fully described my invention, what I claim is:

1. A grading machine comprising a front 95 A shaped adjustable frame work, adjustable cutter blades secured to the frame work, a series of rollers mounted in said frame work, means for adjusting the frame work relative to the rollers, a rear rectangular shaped 100 frame work secured to the front A shaped frame work, a series of rollers mounted in the rectangular frame work overlapping the rollers mounted in the A shaped frame work, and a pulling arm secured on each side of 105 the A shaped frame work.

2. A grading machine comprising a pair of channel beams hinged together at the forward ends, one projecting beyond the other, cutter plates adjustably mounted on said 110 channel beams, pulling arms pivotally secured to said channel beams, T-bars secured intermediately of the ends of said channel beams, swivel bearings secured to said channel beams, a shaft mounted therein, a series 115 of rollers mounted on said shaft, a rectangular frame work secured to the rear ends of the channel beams, roller shafts mounted in said rectangular frame work, a series of rollers mounted on said shafts, and a pivoted 120 drag mounted in the path of travel of the loose material produced by the cutter plates.

3. A grading machine comprising a pair of channel beams hinged together at the forward ends, one projecting beyond the other, cutter plates adjustably mounted on said 125 channel beams, pulling arms pivotally secured to said channel beams, T-bars secured intermediately of the ends of said channel beams, swivel bearings adjustably mounted 130

- on said channel beams, a shaft mounted therein, a series of rollers mounted on said shaft, a rectangular frame work secured to the rear ends of the channel beams, roller shafts adjustably mounted in said rectangular frame work, a series of rollers mounted on said shafts, and a pivoted drag mounted in the path of travel of the loose material produced by the cutter plates.
- 10 4. A grading machine comprising a pair of channel beams hinged together at their forward ends so that they may be adjusted relative to each other, one of which projects beyond the other, T-bars connected to said 15 channel beams, a series of rollers mounted
- between said channel beams and capable of being adjusted thereto, a rectangular frame connected to the rear ends of said channel beams, adjustable cutter plates secured to said channel beams, pivoted pulling arms 20 connected to the channel beams, and a drag secured to the rear end of each channel beam.
- In testimony whereof I have signed my name to this specification in the presence of two subscribing witnesses.

EDWARD PRENDERGAST.
